REFRIGERATION DEVICES FOR INDIVIDUAL GLASS VESSELS

Frederick W. McDonald, Elmhurst, Ill., assignor to A & W Products Incorporated, Santa Monica, Cal.f., a corporation of California

Filed Oct. 3, 1957, Ser. No. 688,020

10 Claims. (Cl. 62—458)

The present invention relates to improvements in means for individually refrigerating vessels, and while adaptable for various types of vessels and containers, such as laboratory beakers, test tubes, and the like, it is especially suitable for individually refrigerating beverage glasses.

Pleasure incidental to drinking of various beverages, of which beer, lemonade, root beer, cola drinks, wines, and cocktails are but a few examples, is enhanced for many persons by serving of the beverage in a chilled glass. Heretofore, however, it has been customary to attain this desirable end by placing the glasses inside of a refrigerated cabinet by the tray-load. Serving of parties or banquets may be thus accommodated, but it is not a satisfactory way to supply chilled glasses for individual customer or drinker demands sporadically or at intermittent intervals.

It is therefore an important object of the present invention to provide novel apparatus by which drinking glasses or other types of vessels are adapted to be individually refrigerated.

Another object of the present invention is to provide apparatus by which a plurality of vessels are adapted to be individually refrigerated so that even though use of the vessels may be sporadic, a continuous supply of thoroughly chilled vessels is available without necessitating opening of any refrigerator cabinet or warming of the remaining or spare chilled vessels.

A further object of the invention is to provide apparatus for individually chilling vessels from within in an efficient, thorough and economical manner.

Still another object of the invention is to provide refrigerating apparatus which makes available immediately at hand a supply of chilled glasses which are maintained in the desired chilled state continuously until removed from the apparatus for use.

Yet another object of the invention is to provide apparatus which will serve the combined functions of a sanitary rack and a refrigeration device.

A still further object of the invention is to provide apparatus which will refrigerate glasses from within without the use of an expendable medium such as carbon dioxide or ice, and without permitting the interior of the vessel or glass to frost.

Other objects, features and advantages of the present invention will be readily apparent from the following detailed description of several preferred embodiments thereof taken in conjunction with the accompanying drawings, in which:

Figure 1 is a top plan view of apparatus for individual refrigeration of vessels according to the present invention;

Figure 2 is an enlarged sectional view taken along line II—II of Figure 1, and showing a drinking vessel received thereon;

Figure 3 is an enlarged sectional view, partly in elevation, taken along line III—III of Figure 1;

Figure 4 is a sectional view generally similar to Figure 2 of another embodiment of the instant invention; and

Figure 5 is a fragmentary view, partly in section, of still another embodiment of the instant invention.

As shown in the drawings:

The principles of this invention are particularly useful when embodied in a refrigeration assembly such as illustrated in Figure 1, generally indicated by the numeral 10. The assembly 10 includes a base 11 having a perimetral rim 12 and a plurality of upwardly directed arbors 13. Each of the arbors 13 communicates interiorly of the base 11 with a refrigerant duct system 14, including a header 14a and a collector 14b, all shown in dashed lines, which in turn communicates with a source of refrigerant 15.

Referring now to Figures 2 and 3, it can be seen that the base 11 comprises a shell defined by a plate 16 disposed to support the entire assembly 10 and a pair of plates 17 and 18. Intermediate the pair of plates 17, 18 and the lower plate 16, there is an insulative fill 19 which is preferable, but which is not essential for operativeness.

The upper surface of the upper plate 18, together with the rim 12, define a tray for supporting and refrigerating a plurality of vessels, such as the vessel V shown in Figure 2. To that end, the upper plate 18 has a plurality of refrigerating elements or units which comprise the arbor-like projections or arbors 13.

Referring to Figure 2, the arbor 13 comprises heat conductive material which is an integral part of the plate 18. While this plate has been illustrated as comprising metal, it is to be understood that any other heat conductive material possessing the requisite structural properties may also be used to this end. Thus the use of heat conductive plastic for this member is within the contemplation of my invention. The arbor 13 has an outer wall or external surface which has a configuration corresponding complementarily to the inner wall or chamber of the vessel V. Preferably, there is a very slight air-gap between the outer wall of the arbor 13 and the inner wall of the vessel V, so that not only are variations in vessel diameter compensated for, but also a slight clearance is provided to preclude or to minimize the formation of a bond therebetween in the event that the vessel V be moist when it is slidably mated with the vessel receiving portion or arbor 13. It is apparent that the greatest heat-transfer efficiency can be achieved when the external wall of the arbor 13 and the inner wall of the vessel V are closely adjacent to each other. However, it is to be understood that advantageous structures may be obtained even where this is not necessarily the case.

Preferably, the axial length of the arbor 13 is such that the mouth or lips of the vessel V are spaced from the horizontal portion of the upper plate 18. Thus, assurance is provided that the lips of the vessel will not be contaminated by any fluid which may be disposed within the tray.

The plate 18 is sealed to the plate 17 around the arbor 13, so that there is produced between the plates 17 and 18 a sealed hollow chamber. If desired, and preferably so, the plate 17 is disposed in spaced complementary relation to the arbor 13 as at 20 so that the chamber 21 defined by the spacing of the plates 17 and 18 is disposed immediately adjacent to the inner walls of the vessel V.

The refrigeration duct system 14 includes a supply line 22 and a return line 23. The supply line 22 and the return line 23 each communicate with the various arbors 13, such communication in this embodiment being in parallel relationship, as between the various arbors 13. It is to be understood, however, that a series or a series-parallel line arrangement may also be used to advantage. Thus the lines 22 and 23 are defined by formations in one of the plates 17. At the point where the supply line 22 communicates with the chamber 21, the plates 17 and 18 joint.

ly define an expansion orifice 23a for refrigerant gas received from line 22.

Accordingly, the chamber 21 communicates through the return line 23 with the low pressure side of the refrigeration unit 15, and communicates via the orifice 23a with the supply line 22 from the high pressure side of the refrigerant source 15. As such, the interior of the arbor 13 may be termed to be an evaporator having a refrigerant passage or chamber immediately below and co-extensive with the vessel receiving portion 13.

Either the portion 13, of the plate 18, or the horizontal portions adjacent thereto may be provided with means for spacing the lips of the vessel V from the upper base surface 18. To this end, a series of four nodes 25, 25, 26 and 27 has been provided integral with the plate 18. The nodes 25, 25 serve the purpose then of spacing the lip of the glass or vessel from the plate 18 and the interior of the vessel V very slightly from the exterior of the arbor 13. This latter spacing is necessary to preclude binding between a previously warm close-fitting glass or vessel and a cold arbor, due to thermal shrinkage of the glass or vessel. The nodes also serve to limit the extent to which the vessel may be rocked with respect to the arbor. In addition, the interior of the node 27 also serves as part of the passage connecting the supply line 22 with the chamber 21, and partly defines the expansion orifice 23a. The node 26, being hollow, serves also to define the connection between the chamber 21 and the return line 23.

Thus the nodes 26 and 27 along with the refrigerant lines 22 and 23 comprise means for connecting the refrigerating means or evaporators together operatively, and in parallel relationship to each other, with a refrigerant source. Such means are supported by the base, and in this instance comprise a part of it.

Accordingly, it can be seen that means has been provided for permanently and fixedly disposing and confining immediately adjacent the outer surface of the arbor and within the arbor, a heat transfer apparatus for refrigerating the arbor from within, and comprising means for conducting fluid refrigerant therethrough in a closed path sealed from the atmosphere, to thereby enable transfer of heat from the inner walls of the vessel supported thereby.

When refrigerant is circulated through the line 22 the arbor 13 is cooled from within at a point immediately adjacent to a relatively warmer portion of the vessel V, whereby heat is transferred from the vessel V to the arbor 13, thereby chilling or refrigerating the vessel V. Since the arbor is relatively received within the chamber of the vessel V, closing the same at its mouth, there is no opportunity for any appreciable amount of moisture laden air to reach the interior of the vessel, and therefore even though the vessel V is refrigerated, there will be no opportunity for moist air to come in contact with such internal cold portion, whereby the deposition of a water condensate, such as frost, is precluded.

Referring now to Figure 4, a slightly different embodiment of the instant invention is illustrated. In this embodiment, the shell includes the same lower plate 16 and a pair of upper plates 30 and 31, the plate 30 being uppermost. The plate 30 is provided with an upstanding arbor portion 32, generally similar to the portion 13, for being relatively received within the chamber of a vessel. Preferably, the arbor portion 32 includes a plurality of small nodes 32a which slightly space the inner wall of the vessel V from the outer surface of the arbor portion 32 to prevent any water film on the glass from forming a bond by freezing. As before, the shell is filled with insulated material 19 if desired. Within the shell, and more particularly within the insulative fill 19, there is disposed a refrigerant duct system including a supply line 33 and a return line 34, communicating with the high pressure and low pressure sides of refrigerant source 15 respectively.

The refrigerant source 15 includes a conventional compressor and condenser which operate on any one of the well-known refrigerant gases such as Freon. However, it is to be understood that the instant invention may also be operated by a circulating liquid refrigerant, such as a brine solution or ethylene glycol. Of course, where a liquid refrigerant is circulated, the orifice between the evaporator and the supply line is omitted.

Referring again of Figure 4, the supply line 33 communicates via an orifice 35 with the interior of the arbor 32 at a point adjacent to the mouth or lips of the vessel.

The return line 34 communicates via a collector tube 36 with the interior of the arbor 32 at a point adjacent to the bottom of the vessel. It can be seen that if any liquid, such as lubricating oil, be discharged through the orifice 35, that the return or collector tube 36 would tend to serve as a trap. Accordingly, to preclude collection of excessive liquid within the arbor 32, a small drain hole 37 is provided in the collecting tube 36 to permit any liquid to be returned and not trapped. Preferably, the hole 37 is so sized that the principal portion of the flow enters at the free end 38.

As in the earlier embodiment, the plates 30 and 31 are sealed together so that they jointly define a sealed chamber 39 therebetween and within the arbor 32.

Accordingly, it can be seen that the instant embodiment includes means permanently and fixedly disposed and confined immediately adjacent the outer surface and within the arbor for refrigerating the arbor from within, said means comprising means for conducting a fluid refrigerant therethrough in a closed path sealed from the atmosphere for transferring heat from the inner walls of the vessel.

The operation of the embodiment of Figure 4 is substantially identical to that of Figure 2 and will be readily apparent.

Referring now to Figure 5, a still further embodiment of the present invention is disclosed. In Figure 5, there is shown a structure including a molded base 40 having a peripheral rim 41 which defines a tray-like portion 42 jointly with the upper surface of the base 40. Projecting from the tray 42 are a plurality of arbors 43 having an external surface formed in complementary relationship to the interior walls of a vessel. Preferably, the material from which the base is formed, has been selected for its heat insulative properties, while the material from which the arbor 43 has been formed, has been selected for its heat conductive properties. Accordingly, the instant structure may comprise two pieces. As illustrated, a refrigerant coil 44 is disposed adjacent to the outer surface 45 of the arbor 43 and is permanently and fixedly disposed and confined therein for refrigerating the arbor from within. The coil 44 communicates with a pair of supply and return lines 46 and 47 which communicate with the source of refrigerant.

In the instant embodiment, the coil 44 has been shown to comprise a metallic coil. However, it is to be understood that the passage defined by the coil 44 may be molded directly into the arbor 43. Thus a parting line or joint would be provided, for example through the centers of the various sections of coil to form, in this instance, a pair of mating frusto-conical members having a channel portion concavely formed in at least one of the mating surfaces. By this structure, it is relatively simple to provide plastic for the outer wall portion of the arbor 43 which plastic has been selected for its heat conductive property.

While the embodiment of Figure 5 is shown constructed for use with a circulating refrigerant, it is to be understood that an orifice may be added so that a gas refrigerant may be used therewith.

Although various minor modifications might be suggested by those versed in the art, it should be understood that I wish to embody within the scope of the patent warranted hereon all such embodiments as reasonably

and properly come within the scope of my contribution to the art.

I claim as my invention:

1. Apparatus for chilling individual open mouth vessels from within comprising, in combination: a pair of plates disposed adjacent to each other; one of said plates having an integral arbor-like formation extending from one side thereof for being relatively received within the vessel; the other of said plates extending into said formation in spaced relation thereto to define an expansion chamber; said plates being sealed together about said formation to seal said expansion chamber; and a supply line, an expansion orifice, and a return line defined by further formations in said plates and communicating with said chamber for evaporating a refrigerant gas.

2. Apparatus for chilling individual open mouth vessels from within comprising, in combination: a pair of plates disposed adjacent to each other; one of said plates having an integral arbor-like formation extending from one side thereof for being relatively received within the vessel, said formation having an external surface corresponding to the interior walls of the vessel; the other of said plates extending into said formation in spaced relation thereto to define an expansion chamber; said plates being sealed together about said formation to seal said expansion chamber; and a supply line, an expansion orifice, and a return line defined by further formations in said plates and communicating with said chamber for evaporating a refrigerant gas therein immediately adjacent to the inner walls of the vessel.

3. In a refrigeration system including an evaporator adapted for connection to a source of refrigerant and to a refrigerant return line, said evaporator having a refrigerant expansion chamber, an expansion orifice communicating with an inlet to said chamber nearest the lowest level thereof for admitting and expanding the refrigerant therein, a refrigerant gas collector communicating the return line with said chamber at a point above the lowest point therein and having an effective flow area substantially greater than the effective flow area of said orifice, and outlet means disposed at the lowest level in said chamber remote from said inlet and communicating with the return line, said outlet means having an effective flow area substantially smaller than that of said collector, and being operative to return any liquid which may otherwise be trapped in said chamber.

4. Apparatus for forming frost only on the exterior of individual open mouth vessels, including in combination: an arbor so supported as to be directed into free moisture-bearing air and adapted to extend through the mouth of one of the vessels while said one vessel is externally exposed to the free air, said arbor being heat conductive and having an external configuration generally complementary to the interior of said one vessel; a plurality of nodes on said arbor, each of said nodes extending therefrom in a manner so as to engage said one vessel and to space it slightly from said one arbor; and means comprising an integral part of said arbor and defining a passage for a mechanical refrigerant, said means being adapted to be connected to a source of refrigerant having a temperature below 32 F.; whereby said arbor is adapted to be refrigerated from within and therefore is adapted to refrigerate said one externally exposed vessel from within to a temperature below 32 F.; said arbor thereby being operative to effect frost formation on only the exterior of said one vessel.

5. Apparatus for forming frost only on the exterior of individual open mouth vessels, including in combination: a base comprising heat-conductive material and having a heat-conductive arbor formation which is integral with said base, said arbor formation being so directed from said base as to extend therefrom into free moisture-bearing air while in use, said arbor formation being adapted to extend through the mouth of one of the vessels while said one vessel is externally exposed to

the free air, and said arbor formation having an external configuration generally complementary to the interior of said one vessel; means within said base defining a passage for a mechanical refrigerant, said means being adapted to be connected to a source of refrigerant having a temperature below 32 F.; means confined within said arbor formation and communicating fluidly with said passage in said base for conducting the refrigerant into and out of said arbor formation; and insulative material in said base adjacent to said passage defining means whereby said arbor formation is adapted to be refrigerated from within and therefore is adapted to refrigerate said one externally exposed vessel from within to a temperature below 32 F.; said arbor formation thereby being operative to effect frost formation on only the exterior of said one vessel.

6. Apparatus for forming frost only on the exterior of individual open mouth vessels, including in combination: a base comprising a pair of generally horizontally extending plates, said plates having portions thereof in flatwise abutting relation against each other, said plates having other portions spaced from each other and jointly defining an elongated refrigerant passage; the upper of said plates including an integral hollow arbor formation extending upwardly therefrom and so disposed as to extend into free moisture-bearing air while in use, said arbor formation being adapted to extend through the mouth of one of the vessels while said one vessel is externally exposed to the free air, and said arbor formation having an external configuration generally complementary to the interior of said one vessel; said plates being so formed that said arbor formation communicates fluidly with said refrigerant passage for receiving refrigerant therefrom and for discharging refrigerant thereto; said plates being jointly adapted at each of the ends of said passage to be connected to a source of refrigerant having a temperature below 32 F.; whereby said arbor formation is adapted to be refrigerated from within and therefore is adapted to refrigerate said one externally exposed vessel from within to a temperature below 32 F.; said arbor formation thereby being operative to effect frost formation on only the exterior of said one vessel.

7. Apparatus for forming frost only on the exterior of individual open mouth vessels, including in combination: a base comprising heat conductive material; a heat conductive arbor having a heat conductive connection with said base and extending upwardly therefrom, said arbor being so disposed as to extend into free moisture-bearing air while in use, said arbor being adapted to extend through the mouth of one of the vessels while said one vessel is externally exposed to the free air, and said arbor having an external configuration generally complementary to the interior of said one vessel; means within said base defining an elongated refrigerant passage disposed to conduct heat away from said arbor, said means being adapted to be connected to a source of refrigerant having a temperature below 32 F.; and a plurality of nodes on said arbor, each of said nodes extending therefrom to engage said one vessel and to space it slightly from said arbor; whereby said arbor is adapted to be refrigerated from within and therefore is adapted to refrigerate said one externally exposed vessel from within to a temperature below 32 F., said arbor thereby being operative to effect frost formation on only the exterior of said one vessel.

8. Apparatus for forming frost only on the exterior of individual open mouth vessels, including in combination: a sealed hollow arbor having an internal cavity, said arbor extending in a generally vertical direction and being so supported at its lower end that its upper end is directed into free moisture-bearing air, said arbor being adapted to extend through the mouth of an inverted one of the vessels while said one vessel is externally exposed to the free air, said arbor being heat conductive and

having an external configuration generally complementary to the interior of said one vessel; a refrigerant supply line; means interconnecting said supply line and said cavity at a first point near the bottom level of said cavity in such manner that the coldest refrigerant will be discharged into said cavity near said lower end; a refrigerant return line; and means communicating said return line with said cavity at a second point near the bottom level thereof and remote from said first point for collecting refrigerant.

9. Apparatus for forming frost only on the exterior of individual open mouth vessels, including in combination: a base comprising a pair of generally horizontally extending plates, said plates having portions thereof in flat-wise abutting relation against each other, said plates having other portions spaced from each other and jointly defining a sealed refrigerant cavity; the upper of said plates including an integral arbor formation within which said cavity is disposed, said arbor formation extending upwardly from the upper of said plates, and being so disposed as to extend into free moisture-bearing air while in use, said arbor formation being adapted to extend through the mouth of one of the vessels while said one vessel is externally exposed to the free air, and said arbor formation having an external configuration generally complementary to the interior of said one vessel; means carried by said base and defining refrigerant supply and return passages; said supply passage being adapted to be connected at one end to a source of refrigerant having a temperature below 32 F., and to discharge refrigerant at its other end into said cavity at a point adjacent to the mouth of the vessel; and said return passage being adapted at one end to collect heated refrigerant from said cavity at a point adjacent to the bottom of the vessel, and to return refrigerant to the source at its other end; whereby said arbor formation is adapted to be refrigerated from within and therefore is adapted to re-

frigerate said one externally exposed vessel from within to a temperature below 32 F., said arbor formation thereby being operative to effect frost formation on only the exterior of said one vessel.

- 5 10. Apparatus for forming frost only on the exterior of individual open mouth vessels, including in combination: a sealed hollow arbor having an internal cavity, said arbor extending in a generally vertical direction and being so supported at its lower end that its upper end is directed into free moisture-bearing air, said arbor being adapted to extend through the mouth of an inverted one of the vessels while said one vessel is externally exposed to the free air, said arbor being heat conductive and having an external configuration generally complementary to the interior of said one vessel; a refrigerant supply line; means defining an expansion orifice interconnecting said supply line and said cavity for admitting the refrigerant in said cavity at a first point near the bottom thereof so that the coldest refrigerant will be discharged into said cavity near said lower end; a refrigerant return line; a collector of gaseous refrigerant interconnecting said return line and said cavity at a second point in said cavity located above said first point, said collector having an effective flow area substantially greater than the effective flow area of said expansion orifice; and means defining an opening disposed at the lowest point in said cavity and remotely from said first point and communicating with said return line, said opening an effective flow area substantially smaller than that of said 15 20 25 30 collector so that any liquid which may otherwise be trapped in said cavity will be returned.
